Charles S. Gooding, Atty.

UNITED STATES PATENT OFFICE.

CORNELIUS KELLEHER, OF NEWBURYPORT, MASSACHUSETTS.

FASTENING DEVICE FOR WINDOW GLASS.

Application filed June 26, 1925. Serial No. 39,684.

This invention relates to a device for fastening glass within a window sash, and has for its object to provide a device embodying therein a plurality of interlocking fastening strips which are adapted to contact with the window sash and bear against the glass therein in a manner to hold said glass in place within said sash without the aid of putty.

10 The invention consists in a device for fastening glass within a window sash as set forth in the following specification, and particularly as pointed out in the claims thereof.

Referring to the drawings:—

15 Figure 1 represents a front elevation of a window sash and pane of glass, a device embodying my invention being illustrated as holding said glass within said sash.

Fig. 2 is an enlarged detail section taken 20 on the line 2—2 of Fig. 1.

Fig. 3 is an enlarged sectional view illustrating portions of two fastening strips interlocking with each other at their ends and also piercing the window sash at their ends.

25 Fig. 4 is a side elevation of the end portions of two fastening strips viewing the latter from the left of Fig. 3.

Like numerals refer to like parts throughout the several views of the drawings.

30 In the drawings, 6 represents a window sash of well known construction, and said sash has a pane of glass 7 mounted therein and seated against a shoulder 8 formed upon said sash.

35 The pane of glass 7 is held in position against the shoulder 8 of the sash 6 by a plurality of fastening strips 9, the latter being formed of sheet metal and being U-shaped in cross section. The end portions 40 of the strips 9 are slotted at 10, thereby forming furcations 11 and the adjacent forked ends of said fastening strips 9 have sliding interlocking engagement one with another as said strips are placed in position

45 against the window sash and pane of glass. The strips 9 are a trifle longer than the distance across the window sash and the extremities of the furcations 11 are curved at 12, and said curved extremities are sharpened so 50 that they will cut into and pierce the window sash when they are forced into position as illustrated in Fig. 3.

In utilizing the fastening strips of this invention as a means for securing a pane of 55 glass 7 within the sash 6, after said glass has been placed within said sash against the

shoulder 8 formed thereon, each fastening strip is placed against the glass as illustrated in dotted lines in Fig. 1, one end of each strip being located at a corner of the 60 sash. The opposite end of each strip is then forced in the direction of the arrow adjacent thereto against the side of the window sash, and as said strip approaches said side, the sharpened extremity of the end portion of 65 the strip will cut into the sash and at the same time the opposite end portion of said strip that is located within the corner of the sash will be forced into said sash and pierce the same. When the strip is in position, 70 both ends of said strip will pierce the sash a sufficient amount to hold said strip tightly therein, and the side of the strip will bear against the glass. As adjacent strips are placed in position, their forked end portions 75 are interlocked one with another and it will, therefore, be seen that when all of said strips are in position, the strips will all co-operate with each other in holding the glass within the sash.

It is evident that in forcing the various strips 9 into position, that the sharpened extremities 12 thereof will cut grooves within the window sash, and said grooves will thereafter remain in said sash so that if the 80 glass is subsequently broken and has to be reset, that when the strips are again replaced, the end portions thereof will be located within the grooves that have formerly been made. It will, furthermore, be evident that if it is 85 so desired grooves may be cut within the sash when the latter is constructed for the purpose of receiving the fastening strips, and the latter may be constructed without sharpened extremities without departing from the 90 spirit of this invention, the said extremities entering the grooves prepared therefor when the glass is placed within the sash, and this latter construction falls within the scope of certain of the appended claims.

I claim:—

1. A device for fastening glass within a window sash comprising a plurality of strips, each embodying therein end portions having curved sharpened edges at their extremities adapted to pierce said sash, said end portions also being adapted to interlock with each other.

2. A device for fastening glass within a window sash comprising a plurality of strips, each embodying therein a pair of similarly formed furcations at opposite ends

- thereof, said furcations interlocking with each other, said strips also being adapted to contact with said sash and bear against said glass.
5. 3. A device for fastening glass within a window sash comprising a plurality of strips, each embodying therein forked portions at opposite ends thereof, the forked portions of adjacent strips being adapted to have sliding interlocking engagement one with the other, the sides of said strips bearing against said glass, and the extremities of said strips penetrating said sash.
- 10

4. A device for fastening glass within a window sash comprising a plurality of U-¹⁵ shaped strips, each embodying therein similarly formed forked end portions having sharpened extremities, said forked portions being adapted to have sliding interlocking engagement one with another, said strips bearing against said glass and said extremities projecting into said sash.

In testimony whereof I have hereunto set my hand.

CORNELIUS KELLEHER.
